[57] CLAIM

The ornamental design for dough cutter or the like, as shown and described.

DESCRIPTION

FIG. 1 is a top plan view of the dough cutter or the like showing my new design;

FIG. 2 is a bottom plan view thereof;

FIG. 3 is a frontal elevational view thereof, all other sides being a mirror image;

FIG. 4 is a cross-sectional view taken along line 4—4 of FIG. 1;

FIG. 5 is a cross-sectional view taken along line 5—5 of FIG. 1;

FIG. 6 is a top plan view of a second embodiment of that shown in FIG. 1;

FIG. 7 is a bottom plan view thereof;

FIG. 8 is a front elevational view thereof, all other sides being a mirror image;

FIG. 9 is a cross-sectional view taken along line 9—9 of FIG. 6;

FIG. 10 is a cross-sectional view taken along line 10—10 of FIG. 6.
